UNITED STATES PATENT OFFICE.

WILLIAM M. WOODWORTH, OF SYCAMORE, INDIANA.

CRATE.

SPECIFICATION forming part of Letters Patent No. 738,588, dated September 8, 1903.

Application filed April 9, 1902. Serial No. 102,060. (No model.)

To all whom it may concern:

Be it known that I, WILLIAM M. WOODWORTH, a citizen of the United States, residing at Sycamore, in the county of Howard and 5 State of Indiana, have invented a new and useful Crate, of which the following is a specification.

The invention relates to improvements in shipping-crates.

10 The object of the present invention is to improve the construction of crates and to provide a simple and comparatively inexpensive one which may be used as a shipping-crate for various articles and which by removing 15 its bottom may be employed in the capacity of a cover to protect trees, plants, &c.

A further object of the invention is to arrange for adjusting the size of the device both laterally and vertically, so as to accommodate 20 it to its various purposes and to accomplish the several adjustments in a very simple and expeditious manner.

With these and other objects in view the present invention consists in the combination 25 and arrangement of parts, as will be herein-after more fully described, shown in the accompanying drawings, and particularly pointed out in the appended claims, it being understood that changes in the form, proportion, 30 size, and minor details may be made within the scope of the claims without departing from the spirit or sacrificing any of the advantages of the invention.

In the drawings, Figure 1 is a longitudinal 35 sectional view of a crate constructed in accordance with the present invention. Fig. 2 is a cross-sectional view thereof on the line 2 2 of Fig. 1. Fig. 3 is a broken section on the line 3 3 of Fig. 1. Fig. 4 is a detail section on the line 4 4 of Fig. 1. Fig. 5 is a detail view of the head of the cover-supporting frame.

Like characters of reference designate corresponding parts in all the figures of the drawings.

45 The body of the present device is in the form of an open - ended cylinder, which is slightly tapered upwardly and formed in three duplicate arcuate sheet-sections 1, 2, and 3, 50 which have their adjacent ends overlapped, as clearly indicated in Figs. 2 and 3 of the drawings, whereby the diameter of the body

may be conveniently increased and decreased by varying the degree of overlap of the body-sections.

To prevent endwise separation of the body members, each pair of overlapped edges is embraced by a loop 4, having a set-screw 5 piercing the inner side thereof and adapted to bear against the inner side of the adjacent 55 body member, so as to draw the two members into snug engagement and also to prevent accidental sidewise displacement of the band. In assembling the body it will of course be understood that the ends of the body-sections 60 are inserted in opposite directions through the respective loops 4. By loosening the set-screws the body members may be slid endwise through the loops to increase or decrease the size of the body. Although it is preferred 65 to form the body sections or members and the loops of metal, so as to provide a strong and durable device, it will of course be understood that other materials may be employed.

To provide for increasing the height of the 70 device and for supporting a cover thereover, each body-section is provided near its upper edge with a transverse slot 6, through which a hooked bolt 7 is projected, the nut 8 of the bolt being upon the outer side of the members 75 and the hook being designed to receive one standard or rod 9 of an arched frame. The upper end portions of the standards are bowed transversely inward across the body and toward the longitudinal axis thereof, so as to 80 telescope within radially - disposed tubular socket members 10 of an arched cross-shaped 85 head, each socket member being provided at its inner side with a set-screw 11, which pierces the member and bears frictionally against 90 the adjacent standard, so that the latter may be adjusted into and out of the head to increase the width of the frame. The lower end 95 portions of the standards are drawn into snug engagement with the inner sides of the body by means of the nuts on the hooked bolts, so as to rigidly support the frame in position, and said standards may be adjusted vertically 100 through the hooked bolts when it is desired to increase or diminish the height of the device.

A flexible cover 12 envelops and is supported by the skeleton frame and is of a length to overlap the body portion, so as to provide a cover for the top of the device. This

cover may be of any preferred character of fabric, waterproof or otherwise, as may be desirable, according to the purpose for which the device may be particularly designed.

5 The body portion of the cloth cover is held snugly against the body of the device by means of a clamping-band formed in three sections 13, 14, and 15, having their contiguous ends overlapped and embraced by the respective loops 16, similar to the loops 4, but having the set-screws 17 upon the outer sides of the loops, so as to be accessible for adjusting the band. As clearly indicated in Fig. 1, the lower edge portion of the cover is fitted 15 snugly between the body of the device and the band, the latter being forced downwardly upon the slightly-tapered body, so as to insure a tight clamping of the cover. The band is adjustable, so as to be readily accommodated to the size of the body and to fit any portion thereof, according to the degree of vertical adjustment of the standards 9.

The crate is provided with a bottom 18, which fits within the lower portion of the body 25 and is provided with a plurality of pendent catches 19, having inclined or cam open-ended slots 20 for engagement with headed studs or projections 21, extending inwardly from the bottom portion of the body-section, so that by 30 turning the bottom the studs or projections may be received in the slots 20, and by reason of the inclination of the latter the bottom will be drawn upwardly into snug engagement with the tapered body. It will of course 35 be understood that the bottom may be removed by turning it in a reverse direction to disconnect the catches 19 from the studs or projections 21. When the device is employed as a shipping-crate, the bottom is in place, 40 and it is particularly adapted for shipping poultry. After it has reached its destination the removable bottom may be detached and it may be used as a cover, as hereinafter explained.

45 Among the various applications of the device when the bottom is detached, it is especially designed to use it in the capacity of a plant and tree protector, and in view of the detachable and adjustable connections between the parts thereof it may be conveniently set up about large trees and bushes, so as to completely inclose the same and protect them from frost and all damaging effects of the weather. For covering small plants it is 50 not necessary to have the device adjustable, and therefore the body may be rigid and the standards 9 fastened thereto, and in view of this manifest change it has not been deemed necessary to illustrate such modification. In 55 addition to protecting trees and plants the device may be employed for protecting haystacks, corn, and fodder standing in the field, and, in fact, anything of this nature which may require protection from the snow, wind, &c. It is furthermore designed to provide the device in much smaller sizes, so as to form covers or protectors for edible articles upon

counters, dining-tables, and the like, so as to afford a protection against flies, dust, &c. In larger sizes the device may be effectively employed as a tent. 70

What I claim is—

1. A device of the class described comprising a body open at the top and bottom and provided on its interior with horizontal projections arranged near the lower end of the body, a removable bottom provided with depending approximately - vertical catches interlocked with the projections of the body and connecting the bottom with the same and supporting 80 the said bottom, and holding the latter against inward and outward movement, substantially as described. 75

2. A device of the class described, comprising a body open at both ends and provided on its interior adjacent to its lower ends with horizontal projections, a detachable bottom arranged within the body and provided with depending approximately - vertical catches having inclined slots receiving the projections, whereby the bottom is connected with the body and is locked against inward and outward movement, substantially as described. 85 90

3. The combination of a body having an open top, adjustable hooked bolts piercing the body, a cover-supporting frame rising above the body and having standards fitted in the hooked portions of the bolts and adjustable vertically therethrough, a textile cover supported upon the frame and overlapping the body, and a clamping-band embracing the cover and the body. 95 100

4. The combination of a body having an open top and provided with a plurality of transverse slots, hooked bolts adjustably fitted in the respective slots, a cover-supporting frame having standards adjustably held in the hooks of the respective bolts, a textile cover supported upon the frame and overlapping the body, and a clamping-band embracing the cover and the body. 110 105

5. A device of the class described comprising a body open at each end and provided on its interior near its upper end with clamping elements, a cover provided with supports extending into the body and detachably engaged by the said clamping elements, a removable bottom arranged within the lower end of the body and provided with depending catches, and means mounted on the interior 115 120 of the body for engagement with the said catches, whereby the bottom is held against inward and outward movement, substantially as described. 120

6. A combined shipping-crate and protector comprising a body open at both ends and provided with extensible sections adjustably connected for varying the size of the body, a detachable bottom fitted within and secured to the lower end of the body, and a cover composed of adjustable sections and adjustably and detachably secured to the body at the top thereof, substantially as described. 125 130

7. The combination of a body formed of end-

wise-adjustable overlapped sections having transverse slots, means for adjustably connecting the sections, hooked bolts adjustably mounted in the slots, a cover-supporting frame having independent standards fitted in the hooks of the bolts, and a textile cover embracing the frame and connected to the body.

8. The combination of a body formed of endwise-adjustable overlapped sections, loops embracing the overlapped portions of the body-sections, set-screws carried by the loops and engaging the adjacent sections, an extensible cover-supporting frame having its members connected to the respective body-sections, a textile cover embracing the frame and the body, and a clamping-band embracing the cover and the body, said band being formed of endwise-adjustable overlapped sections, and having loops adjustably embracing the overlapped portions and provided with set-screws for engagement with the adjacent band-sections.

9. The combination of a substantially cylindrical upwardly-tapered body formed in overlapped endwise-adjustable sheet-sections

provided with transverse slots, loops adjustably embracing the overlapped portions of the sections, set-screws piercing the loops and engaging the adjacent sections, a cover-supporting frame embodying a head having substantially radial open-ended sockets, set-screws piercing the undersides of the sockets, standards rising from the inner sides of the body with their upper ends fitted in the sockets into adjustable engagement with the set-screws, hooked bolts adjustably fitted in the slots of the body and engaging the respective standards, a textile cover embracing the frame and the body, and a clamping-band embracing the cover and the body, said band being formed of endwise-adjustable overlapped sections having loops embracing the overlapped portions and provided with set-screws to adjustably connect the sections.

In testimony that I claim the foregoing as my own I have hereto affixed my signature in the presence of two witnesses.

WILLIAM M. WOODWORTH.
